RETAINING DEVICE FOR STORAGE CONTAINERS

Anthony W. Peters, West Roxbury, Mass., assignor of one-half to Theodore P. Whittemore, West Roxbury, Mass.

Application January 18, 1933. Serial No. 652,297

6 Claims. (Cl. 215—100)

This invention relates to improvements in retaining devices for storage containers. More especially it relates to a combined clasp, locking means and handle which has a particular utility 5 for facilitating the handling of a heavy and/or bulky container, and for securing a container effectively and safely on a supporting structure for controlled discharge of contents. The invention will be herein described and illustrated in connection with a fuel oil supply bottle of ordinary 10 type, mounted inverted, for feed to a kitchen range oil burner; but it may be employed in various other connections, such as for containers of beverages invertedly mounted for valved dispensation of contents in retail trade.

Range oil burners customarily are supplied with fuel from a storage container inverted nearby at an elevation sufficient for gravity to feed its oil to the burner from the intermediary cup 20 into which the bottle mouth dips. The container may be assumed to be of a standard glass bottle type, holding several gallons, set mouth down in a cup-like reservoir from which the feed pipe leads to the burner. Such a reservoir usually is 25 supported on a vertical standard, a pipe rising from a base on the floor; and horizontal spring jaws customarily extend out from a higher part of this round pipe standard, to grasp the upper portion of the bottle.

30 The handling of these bottles when full, and their removal when nearly empty, is difficult for some persons, especially the lifting, inverting and setting of the bottle on its support for proper gravity feed. A handle has been provided at the 35 neck end, but at the large end the smooth, slippery glass surface has had to be grasped as best one could in lifting, balancing and shifting the bottle into its proper place on the support. As the mounting of a bottle has to be accomplished 40 rapidly, to prevent slopping out of oil from the inverted bottle mouth, the mounting operation involves risk of dropping the bottle. This danger is so great, and breakage so frequent, that glass bottles are being abandoned for steel, although 45 steel is in other respects much less desirable.

It is an object of the present invention to eliminate hazard, incident to the handling of such containers, and at the same time to make the lifting, inverting and positioning of a full bottle 50 of oil easier—especially a much easier task for a woman.

A part objective to this end is the providing of convenient and effective means whereby the body of such a large bottle may be gripped safely 55 in one's hand, enabling the bottle as a whole to be securely held and tipped by both hands.

Such means is, to incorporate a handle or grip as an integral part of a clasp which rigidly encircles the body of the bottle.

60 Another feature is to provide means fast to said

clasp and readily attachable to and detachable from the standard which supports the bottle, such as a spring clamp.

A further feature is to provide an instant and convenient locking device for the clamp on the 65 standard.

And another defect of prior devices is removed by preventing any accidental horizontal knocking of the supported bottle around the standard, from 70 position over its delivery cup.

The invention attains these results by means of a combined bottle handle, bottle clasp, spring clamp, and lock for the spring clamp. A single long strip of stiff and strong metal, with slightly elastic tip ends, may be bent at its central portion 75 into a suitably small hand grip, for handle; and be formed semi-circularly, on each side of said handle, to surround and clasp intimately the container or bottle which is to be held; these two semi-circular clasping portions being secured together integrally at the said handle side of the bottle, and being fastened together at the bottle's 80 opposite side, where they approach each other and can be riveted, bolted or mechanically pinched together; and continuing beyond this fastening to their engagement with bottle-supporting 85 upright standard.

For the engagement with the standard the appropriate parts of the clasping strip are preferably spring tempered, and are set bowed slightly 90 away from each other, and then back again, to provide a narrow non-circular bowed space within which a non-circular portion of a supporting standard may enter and be pinched by resiliency of the metal strip. The extreme ends of the 95 strip beyond the said bowed portions are set in a V-formation to constitute a throat through which the standard can enter, spread them, and enter the bowed space,—when the clasped bottle is thrust toward the standard. The resiliency of 100 the metal strip will then close the strip end portions together around the standard, and may suffice to maintain the clasped bottle against displacement away from the standard, and against rotatory displacement around the standard. 105 However, I prefer to lock the strip ends positively in their pinching relation to the standard. A simple U-shaped staple suffices for this lock. When slipped over the strip ends, just back of 110 their spreading tips, such a staple both prevents their spreading and is itself held by gravity. This ensures the maintenance of the simple and convenient, yet entirely effective, connection of clasped bottle to supporting standard.

It is intended that the patent shall cover, by 115 suitable expression in the appended claims, whatever features of patentable novelty exist in the invention disclosed.

In the accompanying drawing.

Figure 1 is a front elevation of an oil supply 120

bottle for a range oil burner, with supporting standard and retaining means embodying features of the present invention;

Figure 2 is a side elevation of the same;

5 Figure 3 is a plan of the device seen in Figure 2;

Figure 4 is a plan of details, the spring fork for engaging the standard, with its locking staple;

10 Figure 5 is a modified construction corresponding to Figure 3.

Referring to the drawing, the inverted container 10 is of bottle shape and may be of glass, as is ordinary, or of other material, to hold a supply of oil or other liquid in position for controlled 15 outflow from the bottle mouth, which latter may rest in a cup-like receptacle 12 reaching out from a vertical supporting standard 14. In the case of oil supply bottles for range oil burners, the standard 14 may be a piece of iron pipe rising from a 20 suitable base 16, and having vertical extent which carries it at least as high as the extreme upper portion of the inverted bottle.

The receptacle 12 preferably is adjustable along standard 14, by means of a set screw 18 or the like; and the oil feed line 20 leads from this receptacle 12.

The invention relates primarily to means for handling and retaining the bottle, to provide against its accidental displacement from its support, and against its slipping from the hands of a person manipulating it. It is at the upper portion of the bottle that the improved retainer is located. The retainer can be made of a single 30 suitably bent length of stiff and strong strip metal. This, as illustrated in Figure 3, is bent at its central portion into the hand grip 22, and, at each side of the grip 22 is formed into a semi-circular clasp portion 24, which halves together are adapted to engage around the circumference of the 40 bottle. The clasp portions 24 are secured together close to the bottle, on the handle side thereof, as at 28, and on the standard side of the bottle, as at 26; and, if it be desired that the clasp be tight on the bottle, one of these will preferably 45 be an adjusting bolt for drawing its ends of the two portions together, in which case an ordinary rivet may be similarly employed at the other side of the bottle. In the arrangement illustrated the handle end is thus adjustable at 28 to an extent 50 sufficient to loosen the clasp for the setting of a bottle into it; and to care for a commercial run of variations in dimensions of bottles which are nominally of the same size.

The strip end portions, brought together at 26, 55 extend onward from the clasp 24, 24, for engaging the supporting standard 15. Immediately beyond 26, each is bowed slightly away from and then toward the other, and then away, in reverse curves, to form the fork 30. This fork may be so 60 made that normally and when empty its prongs contact together in the position illustrated in Figure 3, or so that they stand slightly spread; but it is represented in Figure 4 with rather an exaggeration of spread of the mutually convex portions of its prongs, thus illustrating how easily a pressure of the diverging tips of the fork against the elliptical edge 15 of the standard would facilitate the further spreading and the projecting of the prongs, one to each side of the standard. The 65 prongs act as spring elements, as the standard 15 comes between them, and spring back with strong enclosing and pinching effect thereon, when the standard reaches the space within the bowed portions of the prongs; and they may be stiff enough 70 to hold that standard there except when the clasp

is withdrawn by a strong force consciously applied by a person.

It is a feature of the invention that this spring clamp may hold the bottle against being accidentally turned around standard 14. For this purpose the upper portion of the pipe standard is flattened as at 15; and the fork 30, with its bowed portion shaped accordingly, engages around this flattened portion, preventing any rotatory movement of the clamped bottle around the standard. 80 Without the flattening the clamp would still retain the bottle on a circular standing pipe, like the lower portion 14.

The strong resilient pinching effect of the fork 30 on the standard 15 will be sufficient in itself, 85 if the parts are suitably designed, to provide and maintain an operatively secure attachment of bottle to standard. I am able however, to ensure against accidental dislocation of the bottle, by locking the prongs of fork 30 in their pinching 90 engagement. A mere U-staple 32, of shape seen in Figure 4, may serve as an effective lock, by being inverted and slipped over the two prongs, as seen in Figures 2 and 3. This mechanically 95 locks the prongs against spreading, and so eliminates all possibility of accidental dis-engagement of the retaining means from the standard. It is adapted to be conveniently tied to a prong of fork 100 30, so as to be always at hand when not in use.

In operation the retaining means may be 105 clasped securely on a bottle, to remain as a permanent adjunct thereof, providing a handle at the end of the body of the bottle. With this in addition to the handle 34, provided as heretofore at the bottle neck, the bottle can be grasped firmly 110 at each end by a person, and the danger of its slipping from control is practically eliminated.

Thus equipped with the two handles or grips 22, 34, a full bottle may be gripped securely in one's 115 two hands, and be safely transported, inverted and positioned on its supporting structure. It is only necessary to set its mouth in the cup-receptacle 12, and to push the upper portion of the bottle against the standard. The prongs of fork 30 will then engage and hold to the standard. By 120 dropping staple 32 over the prongs, the whole becomes locked.

The form of handle 22' illustrated in Figure 5 is somewhat simpler, requiring fewer bends of the metal strap 24'. In this case the adjustment 125 for variation of bottle size, or for clasping the bottle tightly, is had by a bolt 28' in place of the rivet 26. In either case, if the cutting of holes at this point be considered objectionable as tending to weaken the clamp, the fastening may be a 130 mechanical binder externally applied, one instance of which would be a staple like 32.

I claim as my invention:

1. In a device for retaining a container or the like at a support beside it, a combination of three 135 loops of strip material, the middle of which loops is permanently secured around the container; another of which loops projects from said middle loop and is open ended, for engaging around the support, there being means for securely closing 140 those open ends beyond that support; and the third of which loops is a closed loop, projecting from the middle loop at a place on the half of the middle loop which is remote from where the second loop projects, and constitutes a handle 145 by which the container may be safely moved.

2. In a device for retaining a container or the like body at a support beside it, a metallic strip formed in three loops, one of which loops is permanently secured around and holding the con- 150

tainer; and the other two of said loops are projections from said container-holding loop and are at positions thereon which are spaced apart around it, one of them being adapted to be a handle for manipulating the container, and the other of them adapted to enclose said support and to hold the whole thereto.

3. A device for retaining a container or the like body at a support beside it, comprising a strip of stiff and strong metal folded double into three successive loop portions, the middle loop of which surrounds the said body while the loop constituted by the middle portion of the strip, projecting from the middle loop, constitutes a handle; and the loop formed by the two end portions of the strip, projecting from the middle loop, constitutes means attaching the strip as a whole and the body which the middle loop encloses to the support; there being a screw bolt connection between those two portions of the strip which come together at one end of the middle loop, whereby the tightness of the enclosing of the body by this loop may be set.

4. A device for retaining a container or the like body at a support beside it, comprising a strip of metal for enclosing the said body and projections therefrom at opposite sides of said body adapted in size, shape and strength for the container body to be handled and its stance secured thereby, one of said projections constituting a handle for the strip and its enclosed body; and the other said projection being adapted to reach horizontally around and be secured behind a vertical support, for holding the whole thereto.

5. A device for retaining a container or the like body at a support beside it, comprising a continuous metal strip, folded double so as to surround said body and to surround said support, there being means binding together between the body and the support; a projection from the strip on that side of the body which is remote from the support, said projection constituting a handle; and the portion of the strip which encloses said support comprising the two ends of the double strip.

6. A device for retaining a container or the like body at support under and beside that body, comprising a strap folded so as to surround said body and thereby to grip it, there being a screw bolt for drawing it tight upon the body, combined with projections extending from opposite location on that part of the strap which lies close around the body, said projections projecting thence stiffly, radially, and approximately horizontally on opposite sides of the body; one of said projections being a handle and the other being means for securing the strap to the support; the basal connection of each said projection, at its said location, spreading laterally toward both directions of strap around the body, whereby the said body may be steadied laterally, while it is resting top-heavily on its said underneath support, by said handle and said means for securing it to the vertical support.
